UNITED STATES PATENT OFFICE

JOHN S. STOKES, OF HUNTINGDON VALLEY, PENNSYLVANIA, ASSIGNOR TO STOKES AND SMITH COMPANY, OF PHILADELPHIA, PENNSYLVANIA, A CORPORATION OF PENNSYLVANIA

METHOD OF FORMING COMPOSITE BOXES

Application filed September 8, 1930. Serial No. 490,432.

My invention relates to the formation of composite boxes formed from a plurality of separate components.

In accordance with my invention, box components adapted to form the bottom and side walls of a box are cut in succession from a continuous strip, as a roll, of box material; preferably, prior to severing of the strip, it is scored, as transversely, to define the bottom and side panels, and thereafter tabs, preferably cut from continuous strips, are applied to project beyond the sides of components and in some forms of my invention also beyond the ends thereof.

At a box forming station, each of the components is brought into proper box-forming position with other box components forming the end walls, preferably also cut from continuous strips, and the projecting tabs folded to attach the separate components to form a box.

Also in accordance with my invention, the strips of box material may be covered with paper, or equivalent, removed from rolls and applied prior to cutting of the components therefrom and preferably also before attachment of tabs thereto.

Further in accordance with my invention, labels may be applied to strips of box material, covered or uncovered, prior to assembly of the components and preferably before severing of the strip.

My invention also resides in methods of making boxes hereinafter described and claimed.

For an understanding of my invention and for illustration of several methods embodying it, reference is made to the accompanying drawings, in which in perspective:

Fig. 1 illustrates the scoring, tabbing, and cutting of a strip of box material;

Figs. 1a and 1b disclose a tabbed box component.

Fig. 2 illustrates the cutting of complementary box components from rolls of box material.

Figs. 3, 4 and 5 illustrate the several successive steps forming a box from the components of Figs. 1a and 2.

Figs. 6 and 7 disclose components similar to those of 1a and 1b with notched tabs.

Fig. 8 is generally similar to Fig. 2, additionally disclosing application of labels to the strips of box material.

Figs. 9 to 11 illustrate the successive steps of forming a box from the components of Figs. 6 and 8.

Fig. 12 illustrates the scoring, tabbing, and cutting of a strip of box material.

Figs. 12a and 13 disclose a box component resulting from the operations diagrammatically disclosed in Fig. 12, the tabs having portions projecting beyond the ends of the component.

Fig. 14 is similar to Fig. 2.

Figs. 15 to 18 illustrate the successive steps of forming a composite box from the components of Figs. 13 and 14.

Fig. 19 illustrates the scoring, covering, tabbing, and cutting of a strip of box material.

Figs. 19a and 20 illustrate the resulting box component.

Fig. 21 discloses the covering of strips of box material from which complementary box components are cut.

Figs. 22 to 24 inclusive illustrate the successive steps of forming a covered and stayed box from the components of Figs. 20 and 21.

Fig. 25 illustrates the scoring, covering, tabbing, and cutting of a strip of box material.

Figs. 25a and 26 illustrate the resulting box component with portions of the tabs projecting beyond the ends of the component.

Fig. 27 is generally similar to Fig. 21 and illustrates the covering of strips from which box ends are cut.

Figs. 28 to 31 illustrate the successive steps of forming a wrapped box from the components of Figs. 26 and 27.

Fig. 32 illustrates the scoring and cutting of box material, the cutting and application of covering material, and the tabbing of box components cut from the roll of box material.

Figs. 32a and 33 illustrate the box com-

ponent resulting from the several operations of Fig. 32.

Fig. 34 illustrates the covering and labeling of strips of box material from which end components are cut, with covering or trimming of one edge of the strip.

Figs. 35 to 38 inclusive illustrate the successive steps of forming a box from the components of Figs. 33 and 34.

10 Fig. 39 is an inverted view of the box shown in Fig. 38.

Referring to Fig. 1, a strip of box material, fed or removed from the roll M, is scored or creased transversely by the knives 1, or equivalent, which engage the lower or under surface of the strip opposite the roll 2, the distance between the knives corresponding to the width of the bottom section b of a box. After each scoring operation, 15 the strip may be fed to such extent that when the knives again pass across the strip the distance between adjacent sections b is equal to twice the height of the side panels s of the box. The dot-dash line indicates 20 where the strip is subsequently cut by the knives 4 to separate the two adjacent side panels s of different box components. Preferably, before the strip is cut to form a component m having the bottom section b and 25 side wall sections s, tab strips t, fed from the rolls T and rendered adhesive by the moistening or glue-applying roll 3, are applied to opposite edges of the strip, normal to the scoring, with part of each extending 30 for a suitable distance beyond the side of the box strip, so that when a component m is cut therefrom the tabs t extend across 35 opposite ends of the component, as clearly indicated in Fig. 1a. The component when 40 bent along the scoring assumes the appearance of Fig. 1b. Preferably, the side panels s are bent inwardly flat against the central portion b to prevent bowing of the sides of the completed box.

45 From the rolls E of box material, corresponding in width to the height of the box to be formed, are cut the end components e by the knives 5, the length of the component corresponding to the width of the box. Preferably, the rolls are disposed adjacent a box-forming station, for example, the form block F, against which the end components e are suitably held, as shown in Fig. 3. The main component m and the 50 end wall components e are maintained in box-forming relation upon the form block structure, and while in this position (Fig. 4) the portions of the tabs t projecting from the side panels s of the main component m are folded into adhesive engagement with the end components e, and thereafter the central portions of the tabs t are bent 55 upwardly into adhesive engagement with the end wall component e completing the

formation of the box (Fig. 5) by uniting the several components e, e and m.

To avoid the gusset fold at the lower corners of the box of Fig. 5, the portions of the tabs projecting beyond the main component m may be notched as indicated in Fig. 6 to divide the projecting part of each tab into a central flap tb and flaps ts extending from the side panels of the wrapper. With the tabs so notched, the side flaps ts may be folded into engagement with the end wall component e (Fig. 10) independently of the central portion tb which is thereafter folded into engagement with the end wall component overlapping the lower portions of the vertical flaps ts, the completed box being shown in Fig. 11.

When desired, labels or the like may be attached to the strip box material before it is cut into components. For example, as 85 shown in Fig. 8, labels l are removed from the stacks L and applied to the under surface of the strip removed from the rolls E before cutting the strip. The end components e with the labels attached may then 90 be transported, against the ends of a form block to which is delivered the main component m, to which they are attached by folding of the projecting portions of the tabs t as above described. It will be ap- 95 preciated that in lieu of affixing labels, the strip may receive impressions from a print- 100 ing roll or equivalent. In either event, the labeling of the box which generically in- 105 cludes printing, is applied to only as much 110 of the box material as is to be used, and there is avoided the usual practice of print- 115 ing or labeling larger quantities than are needed because of inevitable mutilation or 120 destruction of some materials or in anticipa- 125 tion of future orders.

Referring to Fig. 12, the tab strips may be applied so that they project beyond the ends of the box component m to provide the turn-in portions tm. As the scored strip is fed from the roll, the tab material removed from the rolls T is applied to the edge of the strip, the tab feeding starting slightly in advance to provide the project- 115 ing portions tm. The knives 4 are oper- 120 ated to cut a component from the strip, and preferably simultaneously the knives (6) are operated to sever the tab strip joining this component and one previously cut. The length of each tab strip between the ad- 125 jacent components is equal to twice the length of a single turn-in portion tm, so that for each reciprocation of the knives 6 a tabbed box component, as indicated in Fig. 12a, is produced. When the knives 4 open, the component cut thereby from the strip is fed forward and the application of the tab strips thereto is effected or com- 130 pleted, the tab feed continuing until the length of each of tabs t beyond the knives

is equal to the length of the components m plus the turn-in portions tm . Simultaneously, the tab strips are being applied to the advancing box strips.

- 5 The notching of the tabs to provide the flaps tb , ts may be effected at any suitable time, either before, after, or simultaneously with cutting of the tabs by the knives 6. The tabbed blank bent into position is shown in Fig. 13, each tab having portions tm projecting above the top edges of the side panels s and flaps ts and tb projecting outwardly beyond the ends of the side panels and bottom panel, respectively.
- 10 15 The main component is transported to a wrapping station, as the form block F, to which there is substantially simultaneously delivered a pair of end components e cut from the rolls E. With the components 20 in box-forming position, the vertical flaps ts at each end of the box are folded into engagement with the corresponding end wall component e (Fig. 16), and thereafter the central tab portions tb projecting from 25 the bottom panel b of the main component are folded upwardly into engagement with the end wall components and into overlapping relation with the vertical flaps ts (Fig. 17). The portions tm projecting above the top edges of the box at the corners 30 are folded downwardly into engagement with the interior of the box (Fig. 18). By turning in the tabs the strength of the box is greatly increased, and permits the use of 35 much thinner tabbing material without sacrifice of strength.

The different boxes thus far described may be made of strips of box material which is unlined or uncovered. Boxes made 40 from unlined board have many uses, particularly as shipping containers or cartons for more finished boxes or packages.

To make covered boxes in accordance with my method, effecting great saving of 45 covering material as well as of box material, sheet covering material removed from a roll C, (Fig. 19) is brought into engagement with the under surface of an unlined strip of box material removed from the roll 50 M, after passing into engagement with the adhesive moistening or adhesive-applying roll 7. The roll C is substantially equal in width to the roll M, though great exactness is not required as the tab strips t removed 55 from the rolls T, which are subsequently applied to the covered strip, conceal any parts of the strip not covered by the cover C. The knives 4 simultaneously cut the box 60 strip, the covering strip and the tabs to form, as shown in Fig. 19a, a covered and tabbed box component adapted to form the bottom and side walls of a box. The projecting part of the tabs may, as in modifications previously described, be notched, slit-

ted, or otherwise cut to form the flaps ts , tb , etc.

Similarly, the strip from which the box ends e are cut are covered by sheet material removed from the rolls K, the knives 5 simultaneously cutting an end component and its applied cover k from the composite strip. The rolls 8 apply adhesive to, or moisten adhesive already upon, the surface of the covering strip adapted to engage the box material. 75

The covered main component m with the tab material projecting therefrom is delivered to a form block structure F against which the covered components e are held. 80 The tab projections ts of the main component are folded into engagement with the covering material k on the end wall components e (Fig. 23), and thereafter the tab portions tb are folded upward into engagement with the covering material k on the end wall components e and to overlapping relation with the flaps ts (Fig. 24). Further saving of covering material may be effected by using rolls k and c , which are 85 somewhat narrower than the strips of box material to which they are respectively applied, relying upon the tabs to conceal the otherwise uncovered part of the box exterior. 90

The modification of my invention shown in Figs. 25 to 31 is generally similar to that just described, but has the additional feature that the tab strips project beyond the ends of the main component so that, as in the modification of Figs. 12 to 18, the upper corners of the box are reinforced by tab structure engaging the interior and exterior thereof. Briefly, after the box strip is 100 scored or creased by the knives 1, covering material removed from the roll C is applied thereto, the knives 4 cutting the composite strip. Before cutting of the strip there may be applied to the composite edges thereof tab strips t removed from the rolls 105 T, the knives 6 cutting the tab strips joining the box component, cut by the knives 4, to one previously cut and to which tab strips have been fully applied. Since it is 110 desired that the tab strip shall extend beyond both the leading and trailing edges of the box component, the application of the tab strip is not completed until after the component has been severed from the box strip by the knives 4. The covered component with the tab strips projecting therefrom, after being bent along the scoring thereof (Fig. 26), is delivered to the form block structure F against which are held 115 end wall components e , cut by knives 5 from the composite strips formed by adhesive engagement between covering strip removed from rolls k and box material removed from rolls E. 120

As will be understood from the descrip- 125

tion of the prior modifications, the boxes are formed by folding the projecting flap sections ts and tb of the tabs into engagement with the covered surfaces of the end wall components, and the portions tm projecting above the top of the box at the corners downwardly into engagement with the interior of the box (Figs. 30 and 31).

In the modification of my invention 10 closed in Figs. 32 to 39 great saving of covering material is effected by omitting completely to cover the bottom of the box. Additionally, the appearance of the box is improved by covering the top edges. After the 15 strip of box material removed from the roll M is transversely scored by the rolls 1, it is cut by the knives 4 forming a leading side wall portion s and a bottom portion b . As the leading edge of the strip approaches the 20 second set of knives 9, covering material removed from the rolls C is pressed by the roll 11 against the box strip, the knives 9 and 10 cutting the strip of covering material so that a part cm thereof projects in 25 advance of the leading edge of the strip, and a portion cb engages the bottom section b of the strip. After the component is cut from the strip by operation of knives 4, it is fed in the same direction towards a third 30 set of knives 6, and during this feeding movement tab material removed from the rolls T is applied to the blank over the covering piece cs . Simultaneously therewith a second covering strip cs is applied to the 35 trailing part of the component, completely covering the trailing side panel, and projecting to the rear to provide the projecting portion cm and the portion cb in adhesive engagement with the bottom portion b thereof. 40 The knives 9 thereafter cut the covering material simultaneously to form a covering strip cs applied to a component already cut from the box material and a component cs applied or being applied to the leading edge 45 of the strip of box material. After the knives 6 have cut the tab strips, completing the production of one box component such as shown in Fig. 32a, the following, partially prepared component is again fed to the 50 right, as viewed in Fig. 32, beyond the knives 6 during which time application of the tab strips to the edge of the component is completed or resumed. In turn, the last step of forming this component is effected 55 by the knives 6 cutting the tab strips. The covered tabbed main component, ready for delivery to the forming station, is shown in Fig. 33.

The rolls K of covering material (Fig. 34) 60 are somewhat wider than the rolls E of box material, so that the covering material after being rendered adhesive by the roller 8 and applied to the box strip projects therebeyond, the rolls 12 or equivalent turning the 65 projecting part of the covering material

over the edge of the strip and into engagement with the other side thereof. The end wall components e cut from the composite strip are transported to a form block, with the covered edge of the components adjacent the top edge thereof, and with the uncovered surface of the components in engagement with the ends of the block. 70

With the components in the position shown in Fig. 36 the flaps ts of the tabs are 75 folded into engagement with the outer or covered surface of the end wall components, and thereafter the flaps tb of the tabs are folded into adhesive engagement with the end walls and the tab flaps ts (Fig. 37). 80 Thereafter the portion cm of the covering pieces cs are folded over the top of and down to engagement with the inside surfaces of the side walls s , the width of the portions cm in engagement with the box being 85 preferably the same in width as the turned-in portions em of the covering material applied to the box end components e , as shown in Fig. 38. The projecting portions tm of the tabs are folded simultaneously with folding of the covering portions cm . It will be understood, however, that the tabs need not project beyond the top edges of the box. 90

Printing or labels may be impressed upon the covering material removed from the roll 95 K after its engagement with the box material.

By omitting the knives 10 the main box component m may be completely covered with a single sheet, i. e., the bottom as well 100 as the side walls will be covered. The box thus formed will have the feature in common with that described of having all of its top edges covered or trimmed.

In all the modifications of my invention, it 105 will be understood that preferably as a main box component is being prepared, end wall components are being simultaneously prepared so that in succession there are produced groups of components ready for 110 transportation and assembly at a box-forming station. All the methods are preferably continuous in that the several steps follow each other without substantial delay, and the adhesive holding the tabs to the main 115 component m is preferably unset when the components are assembled in box-forming relation ready for attachment to each other by the projecting tab material.

While all of the steps of the several methods described may be performed manually, at least several of them may be effected by known mechanisms. For example, in pending Rider application Serial No. 460, 120 859, filed June 13, 1930, there is shown a box machine for cutting box components from continuous strips fed from rolls, and for delivering a group of box components to the form block of the machine which supports them temporarily in box-forming position 125 130

during their attachment to each other by tabbing or other sheet material.

It will be understood that other modifications may be effected without departing from the spirit of my invention whose scope is defined by the appended claims. At least some of the broader aspects of the disclosure herein, are comprehended by claims of my copending application Serial No. 464,833, filed June 30, 1930.

What I claim is:

1. The method of making boxes which comprises adhesively applying tab material to a strip of box material with portions thereof projecting beyond said strip, severing the strip and tab material applied thereto to form a component adapted to be the bottom and side walls of a box, bringing end wall components in engagement with said first component in box-forming position, and folding the projecting tab portions into adhesive engagement with said end wall components.

2. The method of making boxes which comprises, adhesively applying tab material to a strip of box material with portions thereof projecting beyond said strip, severing the strip and tab material applied thereto to form a prepared component, applying a label to another strip of box material, severing said other strip to form a labeled box component, bringing said components in position to form walls of a box, and folding the projecting tab material into adhesive engagement with said labeled component.

3. The method of making boxes which comprises, cutting box components from continuous strips of box material, applying tab strips to certain of said components before their severance with portions thereof projecting from the components, applying labels to certain of said components before their severance, assembling each group of components in position to form a labeled box, and folding the projecting tab portions to attach the assembled components.

4. The method of making boxes which comprises, adhesively applying tab material to an uncovered strip of box material with portions thereof extending beyond said strip, severing the strip and tab material applied thereto to form a component adapted to form the bottom and side walls of a box, cutting end wall components from uncovered continuous strips of box material, bringing said end wall components into engagement with said first component in box-forming position, and folding the projecting tab portions into adhesive engagement with said end wall components.

5. The method of making boxes which comprises, adhesively applying tab material to a strip of box material with portions thereof projecting from the sides of the strip, independently severing said strip and tab

material to form a box component with portions of the tabs projecting beyond the ends of the component, bringing another component into engagement with said first component in position to form walls of a box, folding the side projecting tab portions into adhesive engagement with said other component, and folding the end projecting tab portions into adhesive engagement with the interior of the box.

6. The method of making boxes which comprises, adhesively applying tab material to a strip of uncovered box material with portions thereof projecting from the sides of the strip, independently severing the strip and tab material to form a box component adapted to form the bottom and sides of a box with the tabs projecting beyond the ends of the component, severing uncovered strips of box material to form end wall components, bringing said first component into engagement with said end wall component in position to form a box, and folding the side projecting tab portions into adhesive engagement with the exterior faces of the end wall components and the end projecting portions over the top of and downwardly into adhesive engagement with the interior faces of said components.

7. The method of making boxes which comprises, adhesively applying sheet material to a strip of box material to project beyond the edges thereof, cutting the strip and attached sheet material to produce a box component adapted to form the bottom and side walls of a box, cutting the projecting sheet material to form flaps, bringing end wall components into engagement with said first component in box-forming position, and folding the projecting flaps at each end of the box into adhesive engagement with the corresponding end wall components and into overlapping adhesive engagement.

8. The method of making boxes which comprises, feeding a strip of box material from a roll thereof, transversely scoring the strip, applying tab strips to the scored strip to project beyond the edges thereof, cutting the tabbed, scored strip to produce box components, each adapted to form the bottom and side walls of a box with tabs co-extensive therewith, feeding other strips of box material from rolls thereof, cutting end wall components therefrom, and uniting a group of components in box-forming position by the tabs projecting from one of them.

9. The method of making boxes which comprises, feeding from rolls equal lengths of strips of box material, covering material, and tab material, effecting adhesive engagement of said strips, cutting the composite strip to produce a covered, tabbed box component adapted to form the bottom and side walls of a box with tab material projecting

70

125

130

beyond the sides thereof, feeding from other rolls and effecting adhesive engagement between equal lengths of strips of box and covering material, cutting the composite strips to produce covered box end wall components, and uniting the components in box-forming relation by the projecting tab material.

10. The method of making boxes which comprises, feeding strips of box material and covering material to like extent from rolls of equal width, effecting adhesive engagement of said strips, cutting the covered strip to produce box components each adapted to form the bottom and side walls of a box, feeding strips of box material and covering material to like extent from rolls corresponding in width to the box height, effecting adhesive engagement of and cutting the strips to form covered box end walls, and uniting groups of components in box-forming position by projecting tab material applied to covered strip material before cutting thereof.

25. 11. The method of making a box which comprises adhesively applying to one side of box material destined to form the bottom and side walls of a box, sheet covering material extending beyond the edges thereof destined to be the top edges of the box side walls, adhesively applying other sheet covering material to one side of other box material destined to form box ends and over the edges of said ends thereof destined to be top edges and into engagement with the other sides, assembling unattached pieces of the covered box material in box-forming position, folding the covering material projecting above the side walls over the top thereof and into engagement with the interior surface, and uniting the covered pieces in box-forming position by tabs overlying the side and bottom edges of the box at each end thereof.

45. 12. The method of making a box which comprises, adhesively applying to one side of box material destined to form the bottom and side walls of a box, sheet covering material extending beyond the edges thereof destined to be the top edges of the box side walls, applying tab strips to the other edges of the material to project therebeyond, adhesively applying other sheet covering material to one side of other box material adapted to form box ends and over the edges thereof destined to be top edges and into engagement with the other side, assembling pieces of the covered material in box-forming position, and while the pieces are in such position, folding the sheet material projecting above the side walls of the box over the top edges thereof into engagement with the box interior and the projecting tab portions into engagement with the end wall pieces.

65. 13. The method of making a box which

comprises, adhesively applying to one side of box material destined to form the bottom and side walls of a box, sheet covering material extending beyond the edges thereof destined to be the top edges of the box side walls, applying tab strips to the other edges of the material to project beyond the said sides and the ends thereof, adhesively applying other sheet covering material to one side of other box material destined to form box ends and over the edges thereof destined to be top edges and into engagement with the other side, assembling the pieces of covered material in box-forming position, and while the pieces are in such position, folding the sheet covering and tab material projecting above the side walls of the box over the top edges thereof into engagement with the box interior and the tab portions projecting from the ends of the side and bottom walls into engagement with the end wall pieces.

14. The method of making boxes which comprises, effecting adhesive engagement of strips of box material and covering material fed from rolls of substantially similar width, independently cutting the strips to produce a box component adapted to form the bottom and side walls of a box and with the covering material projecting beyond the ends thereof, applying tab material fed from rolls thereof to said component to project beyond the sides thereof, effecting adhesive engagement between other strips of box material and covering material fed from rolls with the covering material projecting beyond the box material, folding the projecting covering material over the edge of and into engagement with the other side of the box material, thereafter cutting the composite strip to form box ends, assembling the box components in position to form a box the covered edges of the end components forming top edges of the box, folding the sheet covering material projecting above the side walls of the box to complete covering of the top edges of the box, and folding the projecting tabs into engagement with the end wall components to unite them with said first component.

15. The continuous method of making boxes which comprises cutting box components each adapted to form the bottom and side walls of a box and box components each adapted to form end walls of a box from rolls of box material corresponding in width respectively to the length and height of the boxes to be formed, adhesively applying strip-like tab material to project beyond strip box material before cutting thereof, and before setting of adhesive on the tab material, assembling in succession the groups of box components in box-forming position and uniting the components of each

group by folding of the projecting tab material.

16. The continuous method of making boxes which comprises cutting box components from strips of box material, applying labels to at least certain of said strips before said cutting, applying tab material to at least one of said strips to project therefrom, assembling in succession the groups of components in position to form a labeled box, and uniting the components of each group by said projecting tab material.

17. The method of making boxes which

comprises, adhesively applying sheet covering material and tab strips to a strip of box material, cutting the composite strip to form box components each adapted to form the bottom and side walls of a box with the tabs projecting at each end from the bottom and side walls, applying sheet covering material to other strips of box material, cutting the composite strip to form box ends, and uniting the components in box-forming position by the projecting tabs.
